UNITED STATES PATENT OFFICE

HAROLD G. RICE, OF CHICAGO, ILLINOIS

HOLDER FOR SOCKET-WRENCH SETS

Application filed November 5, 1926. Serial No. 146,360.

This invention relates to holders for holding a socket wrench set which consists of a plurality of sockets of graduated sizes and a bent end handle member adapted to be interchangeably used with any of the sockets.

The objects of the invention are to provide means for holding a socket wrench set such as above described in a neat and orderly compact arrangement; to provide a holder which 10 can be manufactured of a single sheet of comparatively thin gauge material, but which will be strong and rigid, although light in weight; to provide a holder which can be produced at a comparatively low cost; to provide 15 a holder which will require no caps or other movably connected parts, and in general, to provide an improved structure of the class described.

Other objects and advantages will be understood by reference to the following specification considered in connection with the accompanying drawing illustrating a selected embodiment of my invention, and wherein:

Fig. 1 is a perspective.

Fig. 2 is a longitudinal section showing a socket wrench set packed in the holder.

Fig. 3 is an end elevation, and

Fig. 4 is a section on the line 4—4 of Fig. 2.

Referring now to the drawings, my improved holder consists principally in a container or housing 10, which in the present embodiment is circular in cross section, and tapers from a small diameter at one end, as at 11, to a larger diameter, as at the other end 35 12. The tapering housing is adapted to receive the set of sockets arranged end to end, and with the smallest socket in the small end of the housing as shown in Fig. 2. The housing is so tapered that the sockets may be progressively arranged in the housing according 40 to size with the largest socket at the large end of the housing, and whereby each socket will abut the end of the adjacent smaller socket.

At the small end of the housing I provide 45 stop means for preventing the smallest socket of the set from passing through the adjacent end of the housing and this means consists in a plurality of inturned ears or lugs 13, as clearly shown in Fig. 1. The ears 13 prevent endwise movement of the smallest socket

through the adjacent end of the holder, and consequently inward movement of the larger sockets is limited, by the above mentioned engagement between the respective sockets, whereby jamming or wedging of the sockets 55 in the tapered housing is prevented.

For holding or locking the sockets in the housing I provide means for positioning the handle member alongside the row of sockets with its bent end projecting over the large 60 and open end of the housing. This means may consist in another tubular member 14, which is substantially uniform in diameter throughout its length, and whose diameter is sufficient to permit insertion of the straight 65 end 15 of the handle therein, as shown in Figs. 2 and 4. The handle is adapted to be positioned so that the bent end 16 thereof projects over the large open end of the housing. The bent end of the handle is thus effective to lock 70 the sockets in the housing.

I prefer to provide the tubular members 10 and 14 of such length that they will extend over a large portion of the bent end of the handle member as shown in Fig. 2, and 75 whereby the wall at the large end 12 of the socket housing will be effective to prevent turning of the handle member in its housing 14 to a position where the bent end 16 would be rendered inoperative to lock the sockets 80 in their housing. In order to permit the withdrawal of the handle member, I provide notches 17 in the side walls of the holder so that ample room is provided for gripping the bent end of the handle member with the 85 fingers. The handle is releasably locked in the housing 14 by means of a pair of inwardly bent ears 18—18 which, as shown in Fig. 3 must be forced outwardly as the handle member is drawn out. The ears 18—18 serve as a 90 spring clip and their tension may readily be adjusted by bending the ears in or out to effect the desired holding tension on the handle member.

In the present embodiment of my invention, I prefer to make the holder of a single sheet of metal, and as clearly shown in Figs. 1 and 4, the sheet may be bent to form the above described tubular members or housings with a comparatively small space inter-

vening where the metal is brought together, as at 19, to separate the two members. In some instances, I find it desirable to secure the two sides of the holder together at the joint 19 by means of welding as indicated at 20—20, at opposite ends of the holder, or by any other suitable means. By thus welding or securing the opposite sides of the holder together, I am able to use comparatively thin gauge metal, while in cases where heavier metal is used, it may be self-sustaining, and need not be thus secured.

In order to strengthen the holder above described, I provide ribs 21 which are pressed outwardly from the metal as clearly shown in Fig. 2. These ribs 21 are effective to strengthen the holder so that it will withstand rough and careless handling, to which holders of this class are commonly subjected, and particularly against forces which would tend to flatten or distort the tubular housings.

I have thus provided a holder which is simple in construction, consisting of only one piece of sheet metal, and which effectively retains a socket wrench set of the class described, in a neat and compact arrangement without adding materially to the weight or to the cost of the set when sold as a single article.

I am aware that various changes may be made in the form, construction and arrangement of parts, without departing from the spirit of the invention as defined in the following claims, which I desire to have construed as broadly as possible, consistent with the state of the art.

I claim as my invention:

1. In a holder for holding a set of sockets in a row and a bent end handle member lengthwise of said row, the combination of an elongated container for receiving the set of sockets and having one end open for permitting insertion or withdrawal of the sockets, and means for releasably holding the handle member with its bent end disposed over the open end of the container to prevent removal of the sockets therethrough.

2. A holder for holding a set of sockets in a row and a bent end handle member alongside the row, comprising an elongated socket receiving means adapted to receive a set of sockets in a row, said receiving means having stop means at one end for preventing movement of the sockets therethrough, and an opening adjacent the other end for permitting insertion or removal of the sockets therefrom, and means for releasably holding a handle member alongside the row of sockets with a portion of the handle member extending over said opening so as to lock the sockets in the receiving means.

3. In a holder for holding a set of sockets in a row and a bent end handle member lengthwise of the row, the combination of an open ended tubular housing for receiving

the sockets, stop means at one end of the housing for retaining the sockets in the holder at that end, and means for releasably holding the handle member with its bent end extending over the other end of the housing for retaining the sockets in the holder at the latter end.

4. In a holder for holding a set of sockets in a row and a bent end handle member lengthwise of the row, the combination of an open ended tubular housing for receiving the sockets, stop means at one end of the housing for retaining the sockets in the holder at that end, and means for releasably holding the handle member with its bent end extending over the other end of the housing for retaining the sockets in the holder at the latter end, and means for preventing sidewise displacement of said bent end.

5. In a holder for holding a set of sockets in a row and a bent end handle member lengthwise of the row, the combination of a tubular housing substantially circular in cross section and of greater diameter at one end than at the other, stop means at the small end of the housing for engaging one end of the smallest socket of the set, said housing being of such diametrical dimensions throughout its length that each socket will engage the adjacent end of the next smaller socket, and means for releasably holding the handle member in packed position with the bent end extending over the large end of said housing for locking the sockets thereon.

6. In a holder for holding a set of sockets in a row and a bent end handle member lengthwise of the row, the combination of an elongated housing for receiving the sockets in a row, said housing being tapered in cross sectional size so as to snugly receive the smallest socket at one end and each succeeding larger socket in regular progressive arrangement and with each socket abutting the adjacent socket, and means at the small end of the housing for preventing removal of the smaller socket through that end, the other end of the housing being open to permit insertion or removal of the sockets therethrough, and means for releasably holding the handle member in packed position along the row of sockets with its bent end extending over said open end thereby to lock the sockets in the housing.

7. A holder for a socket wrench set, comprising a tubular member tapered in cross-sectional size from one end to the other and another tubular member substantially uniform in cross-sectional size throughout its length and extending along side said tapered member, said members being formed of a single sheet of metal, and each being open at one end for permitting insertion or removal of parts of the wrench set.

8. A holder for a socket wrench set, comprising a tubular member tapered in cross-

sectional size from one end to the other and another tubular member substantially uniform in cross-sectional size throughout its length and extending along side and secured to said tapered member, each of said tubular members being open at one end to permit insertion or removal of parts of the socket wrench set.

9. A holder of the class described comprising a pair of spaced, but integrally united side members, each having a longitudinally extending marginal portion bent inwardly towards each other so as to form a longitudinally slotted housing and both of said side members having a corresponding intermediate longitudinally extending portion bent inwardly towards the other side member so as to divide said housing into two longitudinally extending compartments, one of said compartments being adapted to receive a plurality of sockets and the other compartment being adapted to receive the handle portion of a bent end handle member with the bent end projecting over the adjacent end of the other compartment so as to close said adjacent end, and means for closing the other end of said socket receiving compartment.
